CONTAINER

Harry Sebell, Newton, Mass., assignor of one-half
to Arthur H. Parker, Lexington, Mass.

Application January 10, 1940, Serial No. 313,180

5 Claims. (Cl. 229—3.1)

This invention relates to containers adapted to hold food products and of that type in which the side walls are made of some fibrous material such as paper board, and the end members are made of sheet metal.

One of the objects of the invention is to provide a container of this type in which the end members and side wall portion are secured together in such a way as to provide not only a gas tight and liquid tight seal, but also so as to withstand considerable internal pressure.

Another object of the invention is to provide a container of this type which is completely lined with Cellophane or some similar lining material.

In order to give an understanding of the invention, I have illustrated in the drawing a selected embodiment of the invention which will now be described after which the novel features will be pointed out in the appended claims.

Fig. 1 is a vertical sectional view through a container embodying my invention.

Fig. 2 is a sectional view of the top end member before it is secured to the body section.

Fig. 3 is a sectional view through the upper end of the lined body section to which the top end member is secured.

Fig. 4 is an enlarged fragmentary sectional view.

The container embodying my invention is indicated generally at 1 and it comprises the body section or side wall portion 2 of fibrous material such as paper board, and two end members 3 and 4 of sheet metal. Containers of this type are commonly used for packaging coffee, cocoa, and various other food products.

As stated above, one feature of the invention relates to the manner in which the end members 3 and 4 are attached to the fibrous side wall 2, this being done in such a way as to provide a connection between the side wall and end members which will not only be liquid tight and gas tight, but which will withstand any reasonable pressure which may develop within the container.

Each end member is formed from a suitable blank to present the upstanding wall 5, which may be referred to as a heel wall portion, and the laterally extending seaming flange 6, as shown in Fig. 2, the wall 5 having a shape to fit within the side wall portion 2. The seaming flange 6 is formed with an annular rib 7 preferably having a V shape. When the end member is to be attached to the side wall portion, it is assembled therewith with the wall 5 fitting within the end of the side wall portion 2 and with the

seaming flange 6 overlying the end edge of said side wall portion. During this assembling operation, the rib 7 is forced into the end edge of the fibrous side wall portion 2, thereby dividing said wall at the edge into the inner and outer parts 8 and 9. After the end member has thus been assembled with the side wall, then the peripheral edge of the end member is rolled into a bead 10 by a suitable seaming tool, which bead encircles the end of the body side wall and constitutes a skirt portion that forms with the heel wall portion 5 a channel in which the end of the wall 2 is received. The bottom of the channel constitutes a seat portion for the end extremity of the side wall 2, the annular rib 7 being formed in said seat portion. In forming the bead or skirt 10 it is pressed or embedded slightly into the exterior face of the side wall 2 as clearly seen in Figs. 1 and 4. The outer part 9 of the divided edge portion of the fibrous side wall is forced outwardly by the rib 7 and when the bead 10 is formed, it will be located beneath such outwardly flaring portion 9 so that this portion 9 of the fibrous side wall will be locked between the bead 10 and the rib 7.

This makes a very effective way of attaching the end member to the fibrous side wall and provides an attachment which not only forms a tight seal but also an attachment which will withstand considerable internal pressure within the container.

If desired, the wall 5 may be knurled or indented as shown at 19, thereby to increase the effectiveness of the union between the end members and the fibrous side wall.

I have shown the end wall 3 as formed with a pouring opening 11 which is surrounded by an upstanding curb 12. 13 indicates a closure cap having a skirt 14 which encircles and frictionally fits the curb 12, thereby making a tight closure for the container. This closure cap 13 is shown as having a tab 15 extending therefrom which is spot-welded to the end member 3, as shown at 16, said tab providing a hinge on which the closure cap 13 may swing from opened to closed position, and vice versa.

The container herein shown is completely lined with Cellophane, and the Cellophane lining is so formed that it provides a seal for the pouring opening when the can is first filled and until it comes into the hands of the consumer.

When the side wall portion 2 is rigidly made, it is provided with a lining 17 of Cellophane, said Cellophane lining being cemented to the inner wall of the body portion 2 and extending the full

length thereof. The blank from which each of the end members 3 and 4 is made is provided with a Cellophane lining 18 which is cemented thereto before the blank is pressed into the desired shape, said blank thus being a two-ply blank and having one ply of sheet metal and another ply of Cellophane.

This two-ply blank is pressed into the desired shape, as shown in Fig. 2, thereby to present the upstanding wall 5 and the seaming flange 6 with the rib 7. When the blank has been given the shape shown in Fig. 2, the Cellophane lining will underlie the body of the end member and will lie on the outside of the vertical wall 5 and on the underside of the seaming flange 6 with its rib 7. When the Cellophane lined end member and the Cellophane lined fibrous side wall 2 are assembled and united, as above described, there will be a Cellophane-to-Cellophane contact between the wall 5 and the inner face of the side wall 2 and the marginal portion of the Cellophane ply will be rolled into the bead 10 with the sheet metal, thereby making an extremely tight and effective joint. The Cellophane lining 18 for the end member 3 having the pouring opening will extend across the pouring opening and thus, when the can is sealed after it has been filled, this Cellophane lining 18 for the end member 3 constitutes an inner seal for the pouring opening which provides a hermetically sealed container, even though the closure cap 13 may be opened.

When the package reaches the consumer, and is to be opened for use, the closure cap 13 is pried off from the curb 12 and swung back into open position as shown in dotted lines, Fig. 1, and then the Cellophane which lies under the pouring opening 11 may be punctured or cut out to give access to the contents of the can.

I claim:

1. A container comprising a body section of fibrous material lined with Cellophane, and end members of sheet metal also lined with Cellophane, each end member having an annular wall fitting within the body portion at its end and a seaming flange which overlies the end edge of the body portion and is formed into a bead that encircles said end edge, the seaming flange of each member being formed with a rib which is embedded in the end edge portion of the body section and which divides said end edge portion into inner and outer parts, the outer part flaring outwardly and being locked between the rib and the bead, one of said end members being provided with a pouring opening which is sealed and

closed by the Cellophane lining for said end member.

2. A container comprising a fibre body section which forms the side wall of the container and an end member of metal having an annular wall fitting within the body section at its end and also having integral therewith a seaming flange portion which overlaps the end edge of the fibre side wall and is formed into a bead that encircles the outer face of said side wall and is embedded therein, the portion of the seaming flange between the bead and said annular wall being deformed to present a V-shaped annular rib which is embedded in the end edge of the fibre side wall, thereby dividing said end edge into an inner part which engages said annular wall, and an outer part which is flared outwardly and is locked between said rib and the bead.

3. A container having a tubular body of fiber material and a metallic end closure, said end closure being formed to include an annular channel defined by heel and skirt wall portions between which the end of said body is tightly clamped and a seat portion for opposing an end extremity of said body, and an annular rib in said channel seat portion and embedded in the end extremity of said body, said skirt having an annular portion pressed into the outer face of the wall of said body and effective to securely hold the rib embedded in said body and extremity.

4. A container having a tubular body of compressible material and a metallic end closure, said end closure being formed to include an annular channel defined by heel and skirt wall portions between which the end of said body is tightly clamped and a seat portion for opposing an end extremity of said body, and an annular rib in said channel seat portion and embedded in the end extremity of said body.

5. A metallic end closure for a tubular container body of compressible material, said closure comprising a body portion, an annular heel wall portion adapted to be inserted snugly within a container body end, a flange portion extending annularly beyond said heel wall portion, the peripheral part of said flange portion being adapted to be bent into generally parallel relation to said heel wall portion to form a skirt portion, which with the heel wall portion provides a container body end receiving and clamping channel, and an annular inwardly directed rib formed in the flange portion and situated midway between said heel wall portion and said skirt portion.
